UNITED STATES PATENT OFFICE.

ALFRED J. MANNING, OF NEW YORK, N. Y., ASSIGNOR TO ANDREW DOUGHERTY, OF SAME PLACE.

DESIGN FOR BACKS OF PLAYING-CARDS.

Specification forming part of Design No. **10,242**, dated September 11, 1877; application filed August 4, 1877.
[Term of Patent 7 years.]

To all whom it may concern:

Be it known that I, ALFRED J. MANNING, of the city, county, and State of New York, have invented and produced a new Design for the Backs of Playing-Cards, of which the following is the specification:

The central panel A is of the form shown, and is inclosed within a border, a, forming therewith corner-pieces B, within which are radiating stems i. Cross-stems e, in the center of the panel, terminate in leaf-like figures f, and from each of the latter extends a flower, f', as shown. Curved lines c, extending between the flowers, inclose a mottled center-piece, h.

I claim—

1. The design for the back of a playing-card, consisting of the border a inclosing cor-

ner-pieces B, ornamented by radiating stems i, substantially as shown and described.

2. The design for the back of a playing-card, consisting of a panel containing the cross-stems e, leaves f, and flowers f', and mottled center-piece h, substantially as shown and described.

3. The design for the back of a playing-card, consisting of the center-piece having the cross-stems and leaves f, substantially as described and shown.

In testimony whereof I have signed my name to this specification in the presence of two subscribing witnesses.

ALFRED J. MANNING.
